(57) **CLAIM**

The ornamental design for a compartmentalized storage box, as shown and described.

DESCRIPTION

FIG. 1 is a front perspective view of the compartmentalized storage box according to the present invention with the cover in a closed position.

FIG. 2 is a rear perspective view of the compartmentalized storage box shown in FIG. 1 with the cover in a closed position.

FIG. 3 is a left side elevation view of the compartmentalized storage box shown in FIG. 1 with the cover in a closed position.

FIG. 4 is a top plan view of the compartmentalized storage box shown in FIG. 1 with the cover in a closed position.

FIG. 5 is a bottom view of the compartmentalized storage box shown in FIG. 1 with the cover in a closed position.

FIG. 6 is a right side elevation view of the compartmentalized storage box shown in FIG. 1 with the cover in a closed position.

FIG. 7 is a rear elevation view of the compartmentalized storage box shown in FIG. 1 with the cover in a closed position.

FIG. 8 is a front elevation view of the compartmentalized storage box shown in FIG. 1 with the cover in a closed position.

FIG. 9 is a front perspective view of the compartmentalized storage box shown in FIG. 1 with the cover in an open position.

FIG. 10 is a rear perspective view of the compartmentalized storage box shown in FIG. 1 with the cover in an open position.

FIG. 11 is a left side elevation view of the compartmentalized storage box shown in FIG. 1 with the cover in an open position.

FIG. 12 is a top plan view of the compartmentalized storage box shown in FIG. 1 with the cover in an open position.

FIG. 13 is a bottom view of the compartmentalized storage box shown in FIG. 1 with the cover in an open position.

FIG. 14 is a right side elevation view of the compartmentalized storage box shown in FIG. 1 with the cover in an open position.

FIG. 15 is a rear elevation view of the compartmentalized storage box shown in FIG. 1 with the cover in an open position; and,

FIG. 16 is a front elevation view of the compartmentalized storage box shown in FIG. 1 with the cover in an open position.
